UNITED STATES PATENT OFFICE.

ALBERT WESTLAKE, OF NEW YORK, N. Y., ASSIGNOR TO THE SANSEAL CORPORATION,
A CORPORATION OF NEW YORK.

BOTTLE CAPPING AND SEALING MACHINE.

1,252,377.

Specification of Letters Patent. Patented Jan. 1, 1918.

Application filed February 25, 1916, Serial No. 80,836. Renewed July 31, 1917. Serial No. 183,816.

To all whom it may concern:

Be it known that I, ALBERT WESTLAKE, a citizen of the United States, and a resident of the city, county, and State of New York, have invented certain new and useful Improvements in Bottle Capping and Sealing Machines, of which the following is a specification.

My invention relates to machinery which is used in the rapid sealing of a continuous succession of bottles or other containers. This involves the seizing, one at a time, of the necessary capping disks or other sealing materials from a constantly replenished supply, subjecting the same to suitable treatment to adapt them for application as closure seals and thereafter applying them to the bottle or other receptacle in such a way as to secure the proper and desired sealing. More particularly the present invention, which is an outgrowth of the machine shown and described in my Patent No. 1,137,820, dated May 4, 1915, has reference to that system of closure operations which is designed to furnish and meet the requirements of what is known as a single service container, by which term is generally understood a bottle or other container or receptacle which is intended to be used only once in the condition in which it is put upon the market. In other words, when once opened the container and seal or closure cannot be reassembled. Such portions of the package, for instance a glass bottle, as may be desired for further use are collected and returned to the manufacturer while the undesirable parts, for instance the paper cap, are thrown away or destroyed. Where both container and cap are of fibrous material it is preferable that no portion should be preserved after once used.

It will be understood that my present invention is not limited to any particular class of merchandise or to any particular form or material of container but is applicable to all such articles as milk, spring water, drugs, preserves and pickles, as are more satisfactorily marketed in such a way that the contents are protected against tampering by reason of the fact that the connection between the closure device and the container cannot be restored without detection when once severed.

In the accompanying drawings I have

selected a milk bottle as the container to be sealed because the protection of milk in transit from the bottle to the consumer is of striking importance with a view to health, cleanliness and the prevention of adulteration or dilution and spread of disease.

In my said patent of May 4, 1915, I have shown a bottle as presented to the capping unit by means of a rotary table. In the present drawings I have illustrated an endless chain feed instead of the rotary table.

The object of my present invention is to provide a bottle capping and sealing machine of simpler and stronger construction and of greater capacity, efficiency and power.

This machine is preferably, entirely automatic so that the attendant has only to keep the feeding stack supplied with sealing disks, to remove the filled and capped bottles and substitute fresh and full bottles. Where occasion requires however, the mechanism can be operated by hand power or foot power.

Figure 1 is a front elevation.

Fig. 2 is a perspective view taken at a point at the right (facing Fig. 1) approximately 120 degrees from the center of the front.

Fig. 3 is a perspective view taken from a point at the left (facing Fig. 1) approximately 120 degrees from the center of Fig. 1.

Fig. 4 is a top plan.

Fig. 5 is a substantially central vertical section.

Fig. 6 is a detail to bring out more clearly some of the operative mechanism.

Same letters indicate similar parts in the different drawings.

A, A, represent the frame work of the machine upon which the moving parts are mounted.

B, is a motor from which power is derived and transmitted to the various parts of the machine.

C, is a stack or feed cylinder in which are piled the sealing disks for capping the bottles as hereinafter explained.

D, is a heating and sterilizing oven in which the disks are detained for a fixed length of time during their passage from the feed cylinder to the bottle.

E, is the plunger head or capping tool by the action of which the disk is molded around the mouth of the bottle.

F, is a table upon which the milk bottles are placed and along which they are fed to and from the capping plunger.

G, is a rotating capping and carrying frame which coöperates in turn with the feed cylinder, the heating oven and the plunger head in the successive steps of the sealing and capping operation.

H, H, indicate a series of bottles in position, traveling along the table F, the center bottle being directly under the capping tool.

I, I, I, I, represent carrier disk rings mounted upon the frame G and so positioned that the rotation of the frame G brings one disk ring directly under the plunger, another directly under the oven and a third under the feed slide at the same instant.

J, (Fig. 4) is a feed slide by which the disks are slipped one at a time from the bottom of the feed cylinder and deposited upon the proper carrier disk ring.

K, is a counterbalance weight by means of which the operating mechanism is enabled to accommodate itself to variations in pressure during the continuous capping and sealing operations.

These are the more prominent features of my improved machine and the power for operating all of these parts is derived from the motor B, through various mechanical devices of which convenient and practical types are shown in the drawings, but which may be modified or varied as desired, and as will be readily understood by persons skilled in the art.

All the operations of my improved machine are timed with reference to each other so that the complete cycle of operations beginning with the picking out of a sealing disk from the stack C, and ending with the delivery of a capped and sealed bottle will be performed regularly for each fixed period during the running of the machine. This period for the machine shown in the drawings I preferably fix at about ten seconds, so that a fresh bottle fully and effectively capped is delivered by the table F every ten seconds.

The motor B is mounted upon a shaft a, which we will call the motor shaft and which is supported by the brackets b, b', secured to the base of the frame A.

This motor shaft carries a pinion c which meshes with a toothed gear d (Fig. 5) on a worm shaft a', journaled in the brackets b'', b'', fastened upon the stem of the framework. This worm shaft carries the worm e, which engages the worm wheel L, mounted on the cam shaft a'', journaled in the frame work. This cam shaft carries the cam M, which acts upon the roller f and by the displacement of this cam all the operations of the capping and sealing mechanism are brought about.

This roller f is mounted upon the free lower end of the compound lever N and is held away from the cam by the weight of the various devices and mechanisms operated by the upper end of said lever, subject to the equalizing effect produced by the counterbalance weight K.

The to and fro movement of the lower arm of the lever N is utilized to reciprocate the plunger head E and thereby operate all the other driven devices as follows:—

The lever is pivoted as at g to the bracket b³, and the upper end is connected by the link h, pivoted to it at g', to the elbow lever O at g''. This elbow lever O is pivoted at g³ to the bracket b³ and the other end at g⁴ to one branch of the counterbalance lever P upon the shaft a³, the outer end of which carries the counterbalance weight K, while the inner end at g⁵ is pivoted to the lower end of the plunger head operating rod Q. This rod extends vertically through the casing E', upon which the plunger head is mounted and is adjustably connected therewith by the screw support i. The up and down thrust of this rod Q thus reciprocates the casing E' and the plunger or capping tool E the necessary distance to effect the proper capping and releasing of the bottle which is capped and sealed thereby.

The rotating carrier frame G is caused to rotate intermittently by means of a rack j, secured to the plunger casing E' so as to move up and down therewith. This rack meshes with a segmental gear d', mounted on a rock shaft a⁴, journaled in brackets secured to the stem of the frame A and, in the form shown in the drawings, adapted to receive a quarter turn to and fro for each reciprocation of the casing E' and having a locking pin k.

This rock shaft a⁴ carries a pawl l (Fig. 6) which engages one of the teeth of the four toothed ratchet wheel m, loosely mounted on the rock shaft a⁴. Secured to this ratchet wheel is a gear wheel d'', which meshes with a gear d³, on the shaft a⁵, journaled in brackets secured to the frame A. The shaft a⁵ carries a beveled gear n, which engages a beveled gear n' on the rotating carrier frame G. It will thus be seen that each reciprocation of the rock shaft a⁴ communicates a quarter turn to the carrier frame G, by means of the pawl l, ratchet m, toothed gears d'', d³ and beveled gears n and n'; and that this intermittent quarter turn occurs for each complete reciprocation of the plunger head E.

The rotary carrier G is provided (as shown in the drawing) with four disks receiving and supporting rings I, I, I, I.

These four rings I, I, I, I, are arranged around the rotary carrier G at equal distances from each other and extend outwardly a sufficient distance to bring each 130

disk ring in succession under the feed slide J (Fig. 1) and subsequently under the oven D and plunger head E, as the carrier G revolves. These disk rings have an opening 5 through them sufficiently large to permit the passage of the elevator plates o, o', (Fig. 1) mounted respectively on the stems p, p', but small enough to permit a sealing disk to rest upon the disk ring during its travel.

10 The upper surface of these rings is provided with grooves which co-act with the sealing fingers in securing a regular and perfect capping of the bottle in the usual manner.

15 The function of the elevator plate o is to receive a capping disk delivered to it by the feed slide J immediately above the disk ring I and deposit the same in its descent upon said ring. The function of the elevator plate o' is to lift the sealing disk from that disk ring which is immediately under the oven D and carry it into the oven where it is heated to the proper temperature; after which said plate brings said heated disk 20 down and deposits it on said disk ring by which it is then conveyed to the plunger head.

The reciprocation of these plates o, o', is caused by a rock shaft a⁶ (Fig. 6) journaled on the frame work A and driven by an arm q, mounted on said shaft and carrying at its outer end a roller r (Fig. 5), which is engaged by a suitable lug on the bottom of the rack j, which causes the shaft 30 a⁶ to rock against the tension of a spring s, (Figs. 2 and 6) fastened to the frame A.

At each end of the rock shaft a⁶ is an arm q' provided at its upper end with teeth t. These teeth mesh respectively with pinions c' on shafts a⁷, journaled in brackets attached to the frame work A and carrying wheels m', each of which carries a steel band s', attached to the stem p or p' of the elevator plates o, o' respectively. 40 These stems p, p', are supported by and slide vertically in the brackets b⁴, b⁵, (Figs. 2, 3, and 6) secured to the frame work A.

45 The feed slide J is made to travel from the bottom of the stack C to the adjacent disk ring I, as follows:—

The feed slide (Fig. 4) travels in the guide way or track u and is provided with teeth t' (Fig. 3) on the under side, which mesh with a pinion c'', shown in dotted lines in Fig. 4 on shaft a⁸. This shaft 55 carries another pinion c³ which, as shown in Figs. 2 and 3 is driven by a rack j' secured to the plunger head E. The capping disks are pressed downward by the weight v and the function of the slide is to receive and carry away the lowest disk at each reciprocation of the slide.

60 The feeding of the bottles H is accomplished by a traveling apron R, which travels over and around the table F. This

70 apron is provided with a series of angular holders w, w, the function of which is to steady the bottles as they stand upon and are fed along by the traveling apron. At the point where the bottles come successively under the capping tool E, the table is provided with an open spring holding device s'', which steadies and centers the bottle, but which is opened by the forward pressure of the bottle to allow it to pass on 75 after it has been capped.

75 The proper tension and traveling of the apron R is secured by the sprockets S, S, S, and S', of which the sprockets S are idlers and the sprocket S' is the driving 80 sprocket. This sprocket is mounted on the shaft a⁹, mounted on the bracket b⁶, depending from the table F and carrying a beveled gear n'' (Fig. 3) which meshes with and is turned by beveled gear n³ (Fig. 85 4) on one end of the jointed crank rod T, on the other end of which is a beveled gear n⁴. This beveled gear and crank rod derive their motion from the beveled gear n' on the rotary carrier G, as before stated. 90

95 It will be understood that in this way an intermittent feed is communicated to the apron R, each step of which corresponds to a quarter turn of the carrier, so timed as to bring a fresh bottle in position 95 to be capped when the plunger E is ready to descend and cap it.

U, is a dating device mounted near the disk stack C and constructed so that the dating stamp operated thereby descends and 100 imprints the date on each disk as it is brought under said stamp by the feed slide J on its way from the stack C to the disk ring I.

V, is a rheostat by which the power of the 105 current which drives the motor B is regulated as desired.

As before stated the various details of devices and mechanisms to bring about the desired steps of operation are only given 110 as types of a practical character and may be largely varied without departing from the spirit of my invention.

The complete operation of my improved machine, as will be readily understood, is 115 briefly as follows:—

The stack C being supplied with sealing disks and a full bottle being placed on the table F, as shown in Fig. 1 (H) to the extreme right of the plunger head E, the machine is started by turning the lever of the rheostat V to transmit the desired current to the motor B.

120 The revolution of the motor shaft is communicated through the pinion c, to the gear d, worm shaft a', worm e, worm wheel L and cam shaft a'', to the cam M. The revolution of this cam displaces the roller f, thus reciprocating the plunger head or capping tool E and plunger head casing E', 130

by means of the compound lever N, elbow lever O, counterbalance lever P and operating rod Q. The plunger head E descends and caps the bottle immediately under it, 5 if, as shown in Fig. 1, a bottle is there together with a sealing disk ready for application. It will be readily understood that when the machine is first started the first three descents of the plunger head will 10 take place before the first bottle H has reached it, but that when the machine is re-started all the descents of the plunger may be utilized in capping.

As the plunger head E ascends, the feed 15 slide J is pushed from under the stack C by means of the rack j', pinion c³, shaft a⁸, pinion c² and teeth t'. The feed slide carrying with it a sealing disk from the bottom of the stack travels along the guide 20 way u, under the dating stamp U and over the disk ring I and elevator plate o, said feed slide opening its jaws and depositing the sealing disk upon said elevator plate. As the plunger descends the feed slide is 25 returned to its initial position under the feed stack, prepared to receive another disk.

At the same time the two elevator plates o and o' descend; plate o depositing upon 30 the disk ring I, through which it travels, the sealing disk which it has received from the feed slide and synchronously the elevator plate o' deposits upon the disk ring I, through which it travels, a heated disk received from the oven D, if there was a disk 35 in the oven when the plate began its descent.

The up and down movements of these elevator plates, as previously explained, are derived from the reciprocation of the plunger head casing E', from the rack j, roller r, arm q, rock shaft a⁶, arm q', teeth t, pinion c', shaft a⁷, wheels m', steel bands s' and stems p, p'.

The rotary carrier G now makes a quarter 45 turn, deriving its motion from the plunger head casing E', by means of the rack j, segmental gear d', rock shaft a⁴, pawl l, ratchet m, gears d², d³, shaft a⁵ and beveled gears n, n'. The result of this quarter turn is to 50 move the disk ring which carries the disk received from the feed slide to a position of rest; to move the disk ring which was at rest to a position under oven D and over the elevator plate o'; to move the disk ring 55 which was under the oven to a position directly under the plunger head E, and to move the disk ring which was under the plunger head to a position directly over the elevator plate o, ready to receive the next 60 feeding disk from the feed slide J.

Meanwhile the bottle carrying apron R has been fed a step at a time to bring the bottles in succession under the plunger head, deriving its motion from the rotary carrier 65 G, through the beveled gears n', n⁴, jointed

crank rod T, beveled gears n³ and n'', shaft a⁹ and sprocket S'.

It will thus be seen that all the upward movements of the elevator plate o' (beginning with the third) carry a sealing disk 70 into the oven D and all descents of the plunger head E (beginning with the fourth from the initial start of the machine) cap a bottle with a heated sealing disk. This process continues automatically as long as the current is on to operate the motor and as long as bottles are provided to be capped and sealing disks are provided to cap them. 75

It will thus be seen that while the general principle and character of the above described machine are the same as of the machine shown in my prior patent above named, I have modified and improved the method of operation and arrangement of the more important operating devices whereby I have secured a more powerful and effective and at the same time a much simpler machine. 85

The detailed construction of the various parts which may be called specific features, 90 as for instance the dating device U, the internal arrangements of the oven D, the details of the capping tool, etc., I do not claim herein.

I claim:—

1. A bottle capping and sealing machine which comprises a capping tool, a heating oven, a disk supplying device, a feed slide whereby sealing disks are taken from said disk supplying device and delivered to the 100 rotary carrier, a rotary carrier whereby said disks are conveyed to said heating oven and capping tool, and a bottle conveyer whereby bottles are supplied in continuous succession to and conveyed away from said 105 capping tool.

2. A bottle capping and sealing machine which comprises a capping tool, a heating oven, a disk supplying device, a feed slide whereby sealing disks are taken from said 110 disk supplying device and delivered to the rotary carrier, a rotary carrier whereby said disks are conveyed to said heating oven and capping tool, a bottle conveyer whereby bottles are supplied to said capping tool, 115 and operating mechanism whereby the operations of said devices are so harmonized as to cap and seal a continuous succession of receptacles.

3. A bottle capping and sealing machine 120 which comprises a capping tool, a heating oven, a disk supplying device, a feed slide whereby sealing disks are taken from said disk supplying device and delivered to the rotary carrier, a rotary carrier whereby said 125 disks are conveyed to said heating oven and capping tool, a bottle conveyer whereby bottles are supplied to said capping tool, and operating mechanism whereby the intermittent operations of said devices are so har- 130

monized as to cap and seal a continuous succession of receptacles.

4. A bottle capping and sealing machine which comprises a capping tool, a heating oven, a disk supplying device, a feed slide whereby sealing disks are taken from said disk supplying device and delivered to the rotary carrier, a rotary carrier whereby said disks are conveyed to said heating oven and 10 capping tool, elevating devices which serve as intervening conveyers whereby the disks

are passed from said feed slide to said carrier and to and fro between said carrier and said heating oven respectively, and a bottle conveyer whereby bottles are supplied in 15 continuous succession to and conveyed away from said capping tool.

ALBERT WESTLAKE.
